UNITED STATES PATENT OFFICE.

WILLIAM G. HOUSKEEPER, OF NEW YORK, N. Y., ASSIGNOR TO WESTERN ELECTRIC COMPANY, INCORPORATED, OF NEW YORK, N. Y., A CORPORATION OF NEW YORK.

ELECTRON-DISCHARGE DEVICE.

Application filed October 27, 1922. Serial No. 597,246.

This invention relates to electron discharge devices and pertains especially to electrode structures wherein the anode is supported from a collar surrounding the stem and supports the other electrodes through the medium of insulating blocks.

An object of this invention is the provision of an anode and supporting structure wherein the mechanical connections between the various elements are materially reduced.

Another object of the invention is the provision of a cylindrical anode and supporting structure therefor composed of a single sheet of metal.

Another object of the invention is the provision of means on the anode for determining the space relation between the anode and the insulating blocks.

These objects are attained by stamping from a sheet of metal a blank comprising relatively wide and narrow rectangular strips of metal connected by a pair of spaced strips and providing on the larger strip a plurality of sets of three integral tabs extending from its edges, the central one of said tabs being longer than the others and rolled to form a post. This blank is then bent to form a flattened cylinder of the wider strip with a set of tabs at each bend and the narrow strip is bent and corrugated to form a collar, the two connecting strips being opposite each other. The posts are adapted to pass through insulating blocks resting on the other tabs, said blocks providing means for supporting the other electrodes.

Referring now to the drawings, Fig. 1 discloses an electron discharge device having an anode constructed in accordance with the invention. Fig. 2 is an end elevation of the anode and its supporting collar. Fig. 3 is a section through the anode on line 3-3 of Fig. 1 and Fig. 4 is a section through the supporting structure on line 4-4 of Fig. 1.

The anode and its supporting structure of a vacuum tube 10 are formed from a single blank of metal comprising a comparatively wide rectangular strip and a narrow rectangular strip connected by a pair of narrow members. The wider strip of metal is bent to form a flattened cylinder 11 and its ends are welded together at 12. The narrow strip is formed into a corrugated collar 13 which surrounds the stem 14 of the vacuum tube 10, its ends being welded together at 15. The

anode 11 is supported from the collar 13 by the members 16 which are arranged medially of the flat faces of the anode. Strengthening plaits 16^a are formed in the anode and its supporting structure and extend longitudinally of each face of the anode along each member 16 and across the collar 13.

A plurality of tabs, preferably three, extend from the curved portions of the anode at each end thereof. The central tab 17 of each set is longer than either of the other tabs 18 and its upper portion is bent or rolled to form a cylindrical post. The tabs 18 are of equal length and are engaged by a face of a block 19 of insulating material having apertures through which the posts 17 pass. The ends of the posts 17, projecting beyond the blocks 19, are flattened and serve to hold the blocks against the ends of the tabs 18, the latter serving to properly space the blocks from the ends of the anode. A cathode 20 and a grid 21 are supported between the blocks 19 in cooperative relation to the anode.

The welding operations in this structure are limited to the joining of the ends of the strips forming the anode and collar respectively and the shaping of the strips into the collar and cylinder are carried on simultaneously. Furthermore, in attaching the blocks 19 to the anode, the use of gauges is unnecessary. The simplicity of the steps of manufacturing this type of anode materially reduces the labor cost, and since the device is formed from a single piece of metal, the possibility of the separation of its elements is obviated.

The invention claimed is:

1. In an electron discharge device, an anode comprising a metallic member, posts projecting from the ends of said member, said posts comprising strips of metal bent into cylindrical form.

2. In an electron discharge device, an anode comprising a flattened metallic cylinder, posts projecting from the ends of said cylinder, blocks of insulating material having apertures to receive said posts, and means to determine the space relation between said blocks and anode.

3. In an electron discharge device, an anode comprising a flattened metallic cylinder, tabs integral with said cylinder projecting from the ends thereof, certain of said tabs

- being formed into cylindrical posts, and flattened to fasten said block against the ends of said tabs.
5. In an electron discharge device, an anode, posts projecting from an end of said anode, said posts comprising strips of metal integral with said anode and bent into cylindrical form, a block of insulating material having apertures to receive said posts, and means to determine the space relation between said block and anode. 20
4. In an electron discharge device, an anode comprising a flattened cylinder, posts projecting from one end of said cylinder, said posts comprising strips of metal integral with the cylinder, and bent into cylindrical form, a tab integral with said cylinder at either side of said posts, and a block of insulating material having apertures to receive said posts, the ends of said posts being 25

In witness whereof, I hereunto subscribe my name this 25th day of October, A. D., 1922.

WILLIAM G. HOUSKEEPER.
